UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

FEEDING MECHANISM FOR SEWING MACHINES.

Application filed March 6, 1918. Serial No. 220,720.

To all whom it may concern:

Be it known that I, ALBERT H. DE Voe, a citizen of the United States, residing at Westfield, in the county of Union and State 5 of New Jersey, have invented certain new and useful Improvements in Feeding Mechanisms for Sewing Machines, of which the following is a specification, reference being had therein to the accompanying drawings.

10 This invention relates to multiple needle sewing machines and particularly to feeding mechanism for such machines.

It is an object of this invention to provide new and improved feeding mechanism for 15 sewing machines of great power and durability.

It is a further object of this invention to provide new and improved feeding mechanism capable of advancing heavy fabric or 20 other materials in a straight line and uniformly under at least two widely separated needles with work-engaging members having a very wide and broad surface for engaging the work.

25 It is a still further object of the invention to provide a feeding mechanism in which the number of feed-dogs may be varied as desired and in which also the trains of mechanism for operating a common carrier for the several dogs may be multiplied 30 as desired to suit the load imposed upon the feeding mechanism by the character of the contemplated work.

In its preferred form the invention 35 consists of a pair of separate and distinct feed-dogs each having toothed sections and operated from separate and distinct actuating eccentrics on a main-shaft located below the work-support through connections including rigidly connected pairs of arms 40 whose free ends vibrate in short arcs which approximate straight lines at right angles to each other.

Fig. 1 is a front side elevation of a portion 45 of the machine in which the invention is embodied. Fig. 2 is a plan view of the feed-dogs and their operating mechanism. Fig. 3 is an end elevation. Fig. 4 is a rear side elevation of the machine. Fig. 5 is a 50 perspective of the mechanism for operating the feed-dogs, and Fig. 6 is a front side elevation of the feed-dog operating mechanism only, the actuating eccentrics and main-shaft being omitted.

The stitch-forming mechanism includes a 55 plurality of needles 1, two being shown, widely spaced apart but it is to be understood that any suitable spacing and number may be employed, secured by screws 2 in a socket in a cross-bar 3 carried by a 60 needle-bar 4 braced as partially indicated at 4' in a manner fully disclosed in my co-pending application Serial No. 230,399 filed April 24, 1918, and actuated in any suitable manner. 65

Cooperating with each of the needles is a thread-carrying looper 5 having its blade portion disposed at an angle to the direction of feed and secured by a screw 6 in a hole in a looper-carrier 7 actuated from 70 an inclined crank embraced by a sleeve 8 in a manner fully shown and described in my prior Patent No. 1,256,880, granted February 19, 1918, so as to move the loopers endwise and sidewise in a manner well 75 known to be desirable in the formation of a double-thread chain-stitch.

The foregoing description relates to a construction which specifically forms no 80 part of the present invention.

The feeding mechanism in which the invention of this application particularly resides will now be described. Each of a plurality of very wide feed-dogs 9, arranged abreast of each other in the direction the 85 work advances, is secured by a screw 10 in a seat 11 of which there are two at the opposite ends of a common carrier 12 in the form of a U-shaped feed-dog supporting bar hinged on a pin 13 loosely supported in 90 the upper end of a rocking frame 14 fulcrumed on a pin 15 secured by screws 16 (of which only one is shown) in bearing lugs 17 rising from the base-plate 18 constituting a portion of the frame of the machine. 95

The main-shaft 19 of the machine is located beneath the feed-dogs and carries an eccentric 20 for imparting lifting movements to the feed-dogs and an eccentric 21 for imparting feeding movements to the feed-dogs. The latter eccentric loosely fits around the shaft 19, and has a slidably adjustable connection with a collar 21' fixed on the shaft (Fig. 2). This adjustment forms no part 100 of the present invention and is fully disclosed in my prior Patent No. 1,148,446, dated July 27, 1915. 105

The mechanism for converting the throw of the adjustable eccentric 21 into feeding movements of the feed-dogs will now be described. Embracing the eccentric 21, which 5 may be adjusted, is an eccentric-strap 22 having a sleeve 23 slidably receiving a pin 24 secured by screws 25 in the boss 26 of an L-shaped member, Fig. 6, having arms 27, 28 in the former of which is a socket 29 10 receiving the end of a counter-shaft 30 supported in bearings in the separated lugs 31 which are integral with the base-plate 18 of the machine and which are indicated graphically by the dotted lines in Fig. 5. At the 15 opposite ends of the counter-shaft 30 and disposed in parallelism are a pair of arms one, indicated by the numeral 28, before mentioned and the other indicated by the numeral 32, the last-named having a split- 20 collar 33 clamped by the screws 34 to the counter-shaft 30. The arms 28 and 32 carry at their upper ends stud-screws 35 tapped into the free ends of arms 36 secured by screws 37 to the hinge-pin 13 which is loosely 25 sustained by the rock-frame 14. By these duplicate trains of connections each of the plurality of feed-dogs 9 is moved back and forth to impart feed and return movements during the operation of the machine from a 30 single actuating eccentric on the main-shaft.

Lifting movements are imparted to the feed-dogs from the eccentric 20 through connections similar to those which have been described. Embracing the eccentric 20 is a 35 strap 40 having integral therewith a pin 41 extending into and slidably in a socket in one leg of an approximately U-shaped rocking frame 42 fulcrumed also on the pin 15 before mentioned which supports the rocker 40 14. The shape of the rocking frame 42 is shown in Figs. 2, 3 and 4. The legs 43 and 44 of the U-shaped rocking frame 42 are tapped to receive the shouldered stud-screws 45 and 46 by which they are connected 45 through the links 47 and 48 to another pair of shouldered stud-screws 49 and 50 tapped into the feed-dog supporting bar 12. By the foregoing described train of connections the throw of the lifting eccentric 20 is utilized 50 to impart up and down movements to the feed-dog to initiate and determine the feed action.

It will be seen that the pin 15 forms a support or mounting for both ends of the feed-dog supporting bar 12, through the rocking frame 14 and pin 13 on the one hand and the rocking frame 42 and links 47 and 48 on the other. By means of the connections previously described feed movements are 55 transmitted from the main-shaft through the frame 14 and pin 13 to the closed end of the bar 12, and lift movements through the frame 42 and links 47 and 48 to the free ends of the bar.

60 65 It will of course be understood that the

eccentrics 20 and 21 secured on the main-shaft 19 are so disposed relative to each other that the components of motion imparted therefrom to the feed-dogs result in moving the feed-dogs in a flat elliptical path. 70

In a double-thread chain-stitch machine where it is desirable to give both endwise and sidewise movements to the loopers, it is highly desirable if not absolutely necessary to locate the looper-carrier and the feed-dog 75 operating mechanism largely on opposite sides of a vertical plane containing the needles in order that the loopers may be operated as close as possible to the throat-plate. In the previously described construction it will be seen that this desideratum has been realized in a multiple needle machine. 80

In any wide gauge sewing machine where at least two of the needles are spaced a wide distance apart it is necessary to feed at the 85 same pace the opposite portions of the work which are simultaneously passing under the needles. In the type of machine which has been described, intended for handling heavy stiff material such as the tops of automobiles, 90 it is necessary to provide a very wide feed-dog in order to get a sufficient grip on the work to insure the equal advance of the portions of work passing under the most widely separated needles. It will be apparent that 95 the present invention provides the wide feed-dogs necessary and that the duplex operating mechanism connecting each of the feed-dogs with a single actuating element on the main-shaft renders the mechanism powerful in 100 operation and durable in service.

Having thus set forth the nature of the invention, what I claim herein is:—

1. In a feeding mechanism for sewing machines, a plurality of separate feed-dogs, 105 a main-shaft located beneath said feed-dogs, an eccentric on said main-shaft, a rocker having a fixed fulcrum located in rear of the main-shaft, a plurality of arms on said rocker extending from said fixed fulcrum 110 toward the main-shaft, substantially vertically arranged links connecting each of said feed-dogs with one of said arms, a sliding connection between said main-shaft and said rocker whereby lifting movements of 115 equal amplitude may be simultaneously imparted to the feed-dogs, and means for imparting feeding movements to the feed-dogs.

2. In a feeding mechanism for sewing machines, a plurality of separate feed-dogs, a 120 main-shaft located beneath said feed-dogs, an eccentric on said main-shaft, a rocker having a fixed fulcrum located in rear of the main-shaft, a plurality of arms on said rocker extending from said fixed fulcrum 125 toward the feed-dogs, substantially horizontally arranged links connecting said arms with said feed-dogs, a sliding connection between said main-shaft and said rocker for imparting feeding movements of equal am- 130

plitude simultaneously to said feed-dogs, and means for imparting lifting movements to the feed-dogs.

3. In a feeding mechanism for sewing machines, a plurality of feed-dogs, a main-shaft located beneath said feed-dogs, two pairs of rigidly connected arms fixedly fulcrumed below the feed-dogs, pairs of angularly disposed links connecting said pairs 10 of rigidly connected arms with said feed-dogs, separate actuating elements on said main-shaft, and sliding connections between each of said elements and each of said rigidly connected pairs of arms for im- 15 parting four-motions to said feed-dogs.

4. Feeding mechanism for sewing machines comprising a feed-bar having a plurality of rigidly connected and spaced apart arms, a feed-bar rocker to which said feed- 20 bar is pivotally connected, a plurality of separate feed-dogs each rigidly mounted upon a corresponding one of said feed-bar arms independently of another of said feed dogs, a main-shaft, feed-lift connections 25 with the main-shaft including an eccentric and a feed-lift rocker having spaced arms each separately connected with a corresponding one of said feed-bar arms, and feed-advancing connections including a

feed-advancing rocker deriving movement 30 from said main-shaft and connected to said feed-bar rocker.

5. In a feed mechanism for sewing machines, a substantially U-shaped feed-dog supporting bar provided with a pivot at its 35 closed end, a plurality of feed-dogs separately secured adjacent the free ends of the legs of the bar, a stationary pin secured in the machine frame, a rocking frame fulcrumed adjacent its lower side on said pin 40 and pivoted adjacent its upper side to the pivot on the feed-dog supporting bar, a counter-shaft under the feed-dogs having arms secured thereto outside the legs of the feed-dog supporting bar, links connecting 45 these arms with the opposite ends of the pivot pin between the feed-dog supporting bar and the rocking frame, a substantially U-shaped frame fulcrumed on the stationary pin and provided with spaced legs extending 50 toward the feed-dogs, links pivoted to these legs and the legs of the feed-dog supporting bar, a main-shaft and actuating means on said shaft for oscillating the counter-shaft and rocking the U-shaped frame. 55

In testimony whereof, I have signed my name to this specification.

ALBERT H. DE VOE.
